UNITED STATES PATENT OFFICE.

BLANCHE WILLIS HOWARD, OF BANGOR, MAINE.

MUSIC-RACK FOR PIANOS.

SPECIFICATION forming part of Letters Patent No. 393,562, dated November 27, 1888.

Application filed December 27, 1887. Serial No. 259,035. (No model.)

To all whom it may concern:

Be it known that I, BLANCHE WILLIS HOWARD, of Bangor, county of Penobscot, State of Maine, have invented an Improvement in Music-Racks for Pianos, of which the following description, in connection with the accompanying drawings, is a specification, like letters on the drawings representing like parts.

The object of my invention is to provide a music-rack adapted to support the music much farther forward than the usual music-rack, so that it can be readily seen by a near-sighted person, and preferably capable of wide ranges of adjustment with relation to the keys of the piano.

The invention consists in a music-rack for application to piano-fortes and the like, constructed and arranged substantially as hereinafter specified and claimed.

Figure 1 is a side elevation of a music rack or support embodying this invention; Fig. 2, a perspective view of a portion of a piano provided with a music-support embodying this invention; Fig. 3, a sectional detail of one of the joints; Fig. 4, a modification to be referred to; and Fig. 5 is an enlarged cross-section on line X X, Fig. 1, of the clamping joint between the telescoping rods.

The rack or music-holder proper, *a*, may be of usual construction, being shown as comprising a base, *a'*, and uprights *a''*, that can be folded down upon the base when required. The said rack *a* is supported on a pair of brackets, each of which is provided with a clamp, *b*, properly shaped to be fastened upon some portion of the piano-forte—as, for example, the top of an upright piano, as shown in Fig. 2. The said clamps *b* are provided with sockets *b'*, in which are supported rods *c*, that may be moved up and down in said sockets, and are fastened at the desired height by clamping devices *b''*. The rods *c* are connected at their ends by joints *c'* with arms *c'' c'''*, shown as made in two parts connected by a joint, *c''*, which joints *c'* and *c''* may be made as shown in Fig. 3, and are adjusted to turn with considerable friction, so that the arms or rods connected by them will remain in whatever position they may be turned to by the operator, and the axis of said joints is horizontal, permitting an adjustment of the parts *c'' c'''* of the arms in a vertical plane.

The arm *c''* is connected by a joint, *d*, with an arm, *d'*, moving telescopically in a hollow rod or tube, *e*, connected by a joint, *e'*, with the base *a'* of the rack *a*, which joint *e'*, like the joints *c' c''*, is made sufficiently tight to prevent the parts from turning except when moved positively by the operator for the purpose of adjusting the position of the rack.

The tube *e* may be made as a split clamping-tube, tapering, substantially as shown, and provided with the binding-nut *e''* to bind the tube in any given position upon the rod *d'*. The rack can also be further adjusted forward or backward or vertically by bending the joints *c', c''*, and *e'*, as indicated by the dotted lines, Fig. 1.

There is a swivel at *e''* between the joint *e'* and base *a'* of the music-rack, and, if desired, the rack may be moved up close to the piano by loosening the clamping device *b''*, so that the rod *c* may turn in the sockets *b'*, thus permitting the arm *c'' c'''* to turn in the horizontal direction until parallel with the piano, the arm *d' e* at the same time turning on the joint *d* to the position parallel with the arm *c'' c'''*. When this operation of turning or folding the arm *c'' c'''* and *d' e* toward the piano is not required, the joint *d* may be omitted, and if it were desired merely to support the rack up over the keys, so as to bring the music near enough for a near-sighted person to see to read without providing for various adjustments, the construction of the brackets might be simplified, as shown, for example, in Fig. 4, in which the rods *c* and arms *c'' c'''* are rigidly connected, and said arms *c'' c'''* move telescopically in the tubes *e''*, connected with the music-rack. This construction admits of a vertical adjustment in the sockets *b'* and a forward and backward movement by the telescope-joint; but the construction shown in Fig. 1 is preferable and more convenient.

In the construction shown in Fig. 1 there is a swivel in the arm *c''* between the joints *c'* and *c''*, as shown at *c''*, which increases the adjustability of the entire structure, so that when the joints *c', c''*, and *e'* are adjusted by the nuts shown in Fig. 3 to turn with suitable friction the said structure will afford sufficient support for the rack *a* and music resting thereon; but the said rack can be readily moved in any direction, either up or down, or to the right.

or left, by the hand of the operator, so as to bring any part of the sheet of music to the desired position.

A music-support of this kind is especially useful when other persons than the pianist are reading from the same score.

I claim—

1. As an improved article of manufacture, a music-supporter composed of clamps *b*, to be fastened to the piano-forte, provided with sockets *b'*, and the rods *c*, vertically adjustable in said sockets, and horizontal arms connected with the lower ends of said rods, and tubes adjustable longitudinally with relation to said horizontal arms, and the rack *a*, and friction hinge-joints *c'*, connecting the said rack with the said tubes, substantially as described.

2. The combination of the rack *a* with the socketed clamp *b*, rod *c*, vertically adjustable in the socket, and jointed arm *c²* *c³*, jointed to the said rod *c*, the rod *d* having a swivel-connection with said jointed arm, the tube *e*, adjustable on said rod, and the friction hinge-joint *e'*, pivotally connecting the rack and the tube *e*, substantially as described. 25

In testimony whereof I have signed my name to this specification in the presence of two subscribing witnesses.

BLANCHE WILLIS HOWARD.
